Attorney.

UNITED STATES PATENT OFFICE

LESHER W. VAN BUSKIRK, OF EASTON, PENNSYLVANIA

DIPPER TOOTH

Application filed May 23, 1929. Serial No. 365,462.

The present invention relates to excavating dippers, and aims to provide simple and effective means for protecting the front edge of the dipper from which the teeth extend.

5 The dipper teeth are carried by the front of the dipper, and project beyond the edge thereof, leaving said edge exposed between the teeth. As a result such edge of the dipper is subjected to severe abrasion and wear, resulting in such edge being worn away between the teeth. This not only reduces the efficiency of the dipper, but also has the tendency of forming notches or recesses in which stones and other objects become wedged, preventing the efficient dipping action and dumping of the dipper. Moreover, the wearing away of the front edge of the dipper between the teeth will weaken the front of the dipper, thereby placing greater strain on 10 the remaining portions to which the teeth are secured, and as a result the front of the dipper is apt to break under the severe strains to which the teeth are subjected in the digging action.

25 In carrying out the present invention the teeth are provided with shields for the front edge of the dipper, and which take the wear and abrasion between the teeth, thereby protecting the front edge of the dipper.

30 With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

40 Figure 1 is a perspective view of a dipper embodying the improvement.

Fig. 2 is an enlarged section of the front edge of the dipper, showing one of the shields of a dipper tooth in side elevation.

45 As shown, the dipper teeth 7 are secured astride the digging edge 8 of the dipper front 9, and the improvements may be embodied in dipper teeth of various kinds, either of one piece as shown, or those comprising reversible or other bases and removable tips.

In carrying out the invention, the teeth 7 are provided at the opposite sides thereof with the outstanding shields 10 of V or U shape, so as to be disposed astride or around the front edge 8 of the dipper, as seen in 55 Fig. 2.

These shields extend close together between the teeth, thereby protecting the edge 8 from wear and abrasion. The wings of the shields extending above and below the front edge 80 portion of the dipper will protect same.

Said shields will take the wear and tear which is normally received by the edge, so that when a tooth is worn out, it may be replaced, thereby also renewing the protection 65 for the front edge of the dipper.

As shown, the teeth 7 are of one piece, but when teeth are employed comprising bases and removable tips, the shields may be integral either with reversible or other bases 70 or the tips.

The shields 10 are arranged astride the crotches of the teeth so as to be disposed astride the edge portion of the dipper when the teeth are attached to the front 9. The 75 shields 10 collectively provide a digging edge in front of the edge 8.

Having thus described the invention, what is claimed as new is:

A dipper tooth having a crotch to fit astride 80 the edge portion of a dipper and having integral outstanding shields at opposite sides, said shields being of U-shape and having wings to extend above and below said edge 85 portion of the dipper.

In testimony whereof I hereunto affix my signature.

LESHER W. VAN BUSKIRK.
